E. R. POPE

ATTACHING MACHINE

Filed Jan. 2, 1925

UNITED STATES PATENT OFFICE.

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

ATTACHING MACHINE.

Application filed January 2, 1925. Serial No. 172.

The present invention relates to machines for attaching objects, as by driving nails through one object into another. Especially is it adapted for securing such projections as the cleats employed upon the bottoms of football shoes. These cleats, as to their horizontal contour, are rectangles elongated in one direction, this major dimension being, in some positions of the cleats upon the shoe, placed 5 longitudinally of the bottom and sometimes transversely. The usual practice followed in attaching these cleats, as I am acquainted with it, is to locate them one by one upon a shoe, and then to drive nails manually through 10 each cleat into the shoe-bottom. Such a procedure, to make the attachment effective and with the cleats symmetrically disposed, is difficult and slow. My invention has for an 15 object the provision of a machine so organized as to enable a relatively unskilled operator to attach cleats to a shoe securely and rapidly.

A feature of the invention leading to the attainment of this object consists of the novel combination with a shoe-support or jack and a cleat-holder, of co-operating pressure means, by which a cleat carried by the holder is attached to the supported shoe. Preferably, the cleat-holder also serves to present the attaching nails to the work. The cleat 20 may be held, with, if desired, a spring or other means to aid its retention, in a recess associated with such a member as the die-block of a nailing machine, while the nails are contained in openings connected with the 25 recess. Since the angular relation of the cleats to the shoe-bottom varies, they should be similarly presented for nailing, and the holder is movable to allow this, and has means to fix it in the desired position. The attaching pressure may be exerted by drivers, which 30 are shown as reciprocating through the nail-openings and cleat-recess. Such an arrangement allows the operator to concentrate upon the guiding of the work to present the proper 35 areas for cleat-attachment, the supply of cleats and nails requiring little attention, and the driving being done mechanically. High 40 operating speed and perfect attachment result.

Another feature of the invention involves the supply of nails to a holding member, which presents them in different relations to a shoe, not necessarily for the attachment of a cleat. For this purpose, transferring or

loading means is provided for delivering the 55 nails to the holding member, this transferring means having a member in which are nail-receiving openings, and being movable to arrange such openings to correspond to those of the holding member. This gives a simple organization, by which the nails may be positioned accurately for driving. To insure that the holding member and receiving member agree in position, so that the just-described delivery may be effected, these elements are together provided with means 60 which controls the delivery of nails. This control may include both a retention of the nails in the transferring means and a prevention of the completion of its full movement. To this end, I have illustrated, as a retaining member, a shutter for the receiving member, released by contact with the holding member when the relation is correct. If, 65 however, the position of the holding and receiving members does not agree, contact between said members is such as to limit the movement of the latter and prevent their 70 nail-delivering co-operation.

The accompanying drawing illustrates one 80 of the several forms which my invention may assume. Here,

Fig. 1 shows my improved cleat-attaching machine in broken perspective;

Fig. 2 is a top plan view of the holding 85 member with the adjacent portions of the die-block;

Fig. 3 is a front elevation of these elements;

Fig. 4, a partial vertical, transverse section through the same parts;

Fig. 5, a top plan view of the nail-receiving 90 portion of the loading mechanism; and

Fig. 6, a vertical section on the line 6—6 of Fig. 5.

Generally, this apparatus may resemble 95 that of the nailing machine of United States Patent No. 446,885, Pope, February 24, 1891. A frame 10 carries a vertically reciprocatory cross-head 12, in horizontal ways in which a jack 14 may slide from a position, as illustrated in Fig. 1 of the drawing, in which the work is applied, to a point beneath the die-block 16 of the nailing mechanism. The die-block has nail-holding openings, later to be described in detail, through which operate 100 pressure members, in the form of drivers 18, depending from a top girt 20 connecting the upper extremities of vertical side rods 22, 22,

which are mounted to reciprocate in the frame. A shoe S appears upon the jack, bearing upon its sole and heel-portions cleats C, which have been attached by series of nails N driven through them into the shoebottom and clinched upon the jack-top. The cleats are shown as rectangular in horizontal section, the side walls c being inclined, they converging outwardly to a horizontal tread-portion d. The jack 14 preferably has a curved horn 24, free to rotate with a spindle 26 and provided with a horizontal work-supporting surface 28, which intersects the axis of the spindle. This relation between the jack-top or horn and the spindle permits the horn to be turned without carrying the work-supporting surface out of the nailing position.

At the center of the die-block is a vertical opening arranged to receive a cleat-holding and nail-holding member 30. In the present instance, this member is furnished by a generally cylindrical plug, which is held against displacement by a screw 32 threaded through the front of the die-block and projecting into a slot 31 in the plug. A shoulder upon the plug at 33 receives the pressure when the elevation of the jack by the cross-head forces the jacked shoe against the plug, which then serves as a work-abutment. A portion 34 of the plug extends below the die-block, and in this portion is a recess 36, similar in form to the bottom of a cleat. That is, the side walls converge inwardly at 38 at substantially the same angles as the walls of the cleat, and meet a horizontal wall 40. This recess receives a cleat for attachment, retention being assured by yieldable fingers 42, 42, which appear as curved leaf-springs fixed to the sides of the plug-portion 34 and having their inturned ends bearing against the walls c of the cleat. Extending vertically through the plug from the upper wall 40 of the recess is a series of nail-receiving openings 44, of which five are here illustrated. The plug also has a second series of openings 46 extending at right angles to the series 44 and symmetrically located with respect thereto, there being a central opening common to the two series. The purpose of the openings 46 will later be stated. The plug 30 is rotatable about an axis passing through it to permit the openings 44 to be selectively located, either for the attachment of a transverse or a longitudinal cleat, the latter relation being shown in Fig. 1 of the drawing. This is effected by a handle 48, a stem 50 of which is screwed into the side of the plug and projects through a slot 52 in the front of the die-block. To secure the openings 44 in their respective operating positions, the body of the handle is yieldably mounted upon the stem, a spring 54 surrounding the stem and acting upon the handle to force it inwardly. When the series of openings 44 is in either of the nailing positions, the

inner end of the handle enters one of two depressions 56 located at the extremities of the slot 52. This latches the plug against rotation; but when the handle is drawn outwardly, the plug is freed and may be turned to its alternative position.

To drive nails held in the openings 44 with their points resting upon a cleat in the recess 36, the drivers 18 are arranged in the same relation as the openings 44 and 46, they being in two series, respectively transverse and longitudinal with respect to the shoe-bottom and to the die-block. As a result of this, in either of the operating positions of the plug 30, the nail-holding openings 44 find one of the crossed series of drivers 18 effective to force the nails through the cleats. The inactive series at this time moves idly in the series of openings 46.

Nails are supplied to the openings 44 in either of the operating positions by transferring mechanism 58. Arranged to oscillate upon the frame about one of the side rods is a loader-arm 60, which may generally resemble that of the machine disclosed in the Pope patent previously referred to. Movement is thus permitted from a nail-receiving position, as illustrated in Fig. 1, to a nail-delivering position over the die-block. The loader-block 62 of this mechanism carries a nail-receiving member furnished by a plug 64, rotatable in a vertical opening 66 shouldered at 68 to support the plug. A screw 70 is threaded through the top of the loader-block, having its head entering a horizontal slot 72, this engagement preventing accidental displacement of the plug upwardly. The screw contacts with the ends of the slot to limit the extent of rotary movement of the plug, this being such that a series of vertical nail-receiving openings 74 may be shifted between a position in which they will register with the nail-holding openings 44, when these are in their transverse relation to the die-block, and one above said holding openings when they are turned longitudinally of the die-block. The plug 64 is latched in either of these nail-delivering positions by a plunger 76 operating in a horizontal bore through the loader-block. This plunger is pressed into retaining engagement with either of two depressions 82 in the side of the plug by a spring 78. At its outer end, this spring abuts against a screw 80 closing the end of the bore. By a suitable force exerted upon the nubbed surface surrounding a portion 83 of the plug which projects above the loader-block, the plunger may be forced out of engagement with the depression, in which it may rest, and the plug turned until the plunger enters the other depression. At the lower end of the plug 64 are ways to receive a horizontally movable shutter or nail-retaining member 84, in which is a series of openings 86. Normally, these are held at one side of the open-

ings 74 by a spring 88 contained in a recess in the plug above the shutter and acting upon a projection 90 rising from said shutter. Movement of the shutter against the expansive force of the spring brings the openings 86 and 74 into registration, so nails previously supported in the last-mentioned opening with their points resting upon the shutter are discharged. Upon the holding plug 30 is an elevated portion 92, having at its inner side a vertical wall 94. When the loader-arm is swung into its nail-delivering position over the die-block, an inclined end 96 of the shutter wipes over the surface 94, producing the just-described alinement of the openings 86 and 74, at the time when these are in registration with the nail-holding openings 44. The nails in the transferring mechanism are therefore delivered in position for driving. If the plug 30 had been turned to the other operating position than that shown in Fig. 1, or with the series of openings 44 lying longitudinally of the die-block, and the plug 64 had been correspondingly turned, the end 93 of the shutter would strike directly against the wall 94 to cause the nail-delivery. If, however, the holding plug 30 has been shifted to its position with the openings 44 longitudinally of the die-block, and a corresponding alteration in the position of the receiving plug 64 has not been made, the face of the plug above the shutter will contact with the surface 94, so that said shutter will not be actuated and the loader-arm will be stopped before the position of delivery is reached, notifying the operator of the error.

In using the machine for the attachment of cleats to shoes, the operator or his assistant supplies a cleat C in the recess 36, pressing the springs 42 aside, the contact of these springs retaining the cleat in place. At this time, the openings 74 of the loader-block plug receive their charge of nails, and this plug and the die-block plug 30 are located in corresponding positions. If a cleat the length of which is to lie longitudinally of the shoe is to be attached, the openings are arranged as illustrated. If a transverse cleat is to be nailed, both plugs are turned through 90 degrees. The operator places a shoe upon the horn of the jack 14, which is in the position shown, with the insole surface opposite the area to which the cleat is to be attached, resting upon the supporting surface 28. The jack is then moved in upon its ways on the cross-head and raised until the shoe-bottom is forced against the under side of the cleat in the holder. Starting the machine causes suitable pressure to be applied to the work by further elevation of the jack and the top girt to descend, carrying the drivers into the openings 44 and 46, the former series pressing the nails out of the openings 44 through the cleat into the sole and clinching them upon the surface 28. The machine, in its operation,

then lowers the cross-head to relieve the pressure upon the work, so that the operator may shift the shoe either bodily upon the surface 28 or by turning the horn with the spindle. If the cleat now to be nailed bears the same relation to the shoe as that just attached, the angular positions of the plugs 30 and 64 remain unchanged, there being only another cleat and a fresh load of nails supplied. But if the succeeding cleat is one which is transverse to the position of that just operated upon, the plugs are rotated to their opposite extreme positions, and the nailing operation performed as before.

Having described my invention, what I claim as new and desire to secure by Letters Patent of the United States is:

1. In a machine for attaching cleats to shoes, a shoe-support, a holder arranged to retain a cleat against movement therein, said holder being movable to present the contained cleat for attachment in different positions on the bottom of a supported shoe, and means movable independently of the holder for attaching a cleat thus held to said supported shoe.

2. In a machine for attaching cleats to shoes, a nail and cleat-holder, a support arranged for the presentation of the forepart and heel-portions of a shoe-bottom to the holder, means for applying pressure to a cleat in the holder, and means for forcing the nails through the cleat while under pressure into the bottom of a shoe upon the support.

3. In a machine for attaching cleats to shoes, a member having a recess formed to receive a cleat and to hold it against movement, a curved horn rotatable in co-operation with the recess, and means arranged to force attaching nails through the cleat held in the recess and into the bottom of the shoe.

4. In a machine for attaching cleats to shoes, a frame, means mounted thereon for supporting a shoe, and means movable upon the frame to present cleats during their attachment at different angles with relation to the bottom of a shoe thus supported.

5. In a machine for attaching cleats to shoes, means for supporting a shoe, means arranged to present cleats with their greatest dimension both longitudinally and transversely of the bottom of a shoe thus supported and means for latching the presenting means in either position.

6. In a machine for attaching cleats to shoes, means for supporting a shoe, means movable to present cleats at different angles with relation to the bottom of a shoe thus supported, and means movable under the power of the machine for driving nails through the presented cleats into the shoe-bottom.

7. In a machine for attaching cleats to shoes, means for supporting a shoe, means arranged to present cleats both longitudinally and transversely of the bottom of a shoe thus

- supported, and sets of nail-drivers arranged to act upon the cleats in both positions.
8. In a machine for attaching cleats to shoes, a die-block, a member movable upon the die-block and provided with a cleat-holding recess and nail-holding openings connected therewith, nail-drivers arranged to reciprocate through the openings in the recess, and a jack co-operating with the die-block opposite the recess.
9. In a machine for attaching cleats to shoes, a shoe-support, a movable cleat-holder, and means arranged to fix the cleat-holder with cleats which it carries in different attaching positions with relation to the shoe-support.
10. In a machine for attaching cleats to shoes, a shoe-support, a rotatable cleat-holder co-operating therewith, and means arranged to turn the cleat-holder about an axis passing through the contained cleat and fix it in different angular positions.
11. In a nailing machine, nailing mechanism, a shoe-support co-operating therewith, and means movable to present an object with a particular dimension arranged either longitudinally or transversely of a shoe on the support.
12. In a nailing machine, a die-block having an opening, and a holder for an object to be nailed movable in the opening between different nail-inserting positions.
13. In a nailing machine, a die-block having an opening, a holder for an object to be nailed rotatable in the opening, and a latch arranged to temporarily secure the holder in different angular positions.
14. In a nailing machine, a die-block provided with an opening extending through it and a slot through the front of the block and entering said opening, and a holding member rotatable in the opening and having a handle projecting through the slot.
15. In a nailing machine, a die-block having an opening, a holder for an object to be nailed movable in the opening, said holder having nail-receiving openings, and drivers operating in the openings.
16. In a nailing machine, a die-block having an opening, a holder for an object to be nailed rotatable in the opening, said holder having series of nail-receiving openings extending at an angle to one another, a latch arranged to retain the holder in angular positions corresponding to the nail-receiving openings, and drivers operating in the openings.
17. In a nailing machine, a die-block, a nail-holding member movable in the block and having series of openings, means arranged to fix selectively the nail-holding member with a particular series of openings in operating relation, and drivers acting in all the openings of the plural series.
18. In a cleat-attaching machine, a horizontal die-block having a vertical opening, a plug rotatable in the opening and provided with intersecting series of nail-receiving openings, a reciprocatory top girt, and intersecting series of drivers mounted upon the top girt and registering with the openings in the plug.
19. In a cleat-attaching machine, a horizontal die-block having a vertical opening, a plug rotatable in the opening and provided with intersecting series of nail-receiving openings, and a handle projecting from the plug through the front of the die-block, said handle being movable into engagement with the die-block to secure the plug in different positions.
20. In a machine for attaching cleats to shoes, a shoe-support, an abutment member situated opposite said support and having a recess with its walls fixed against movement during the attaching operation and provided with an open side through which a cleat is received and in which it is presented to a supported shoe, and means arranged to retain the cleat in the recess during presentation.
21. In a machine for attaching inclined cleats to shoes, a shoe-support, an abutment member situated opposite said support and having a recess provided with side walls converging inwardly to conform to a cleat, and spring devices engaging the inclined walls of the cleat to retain it in the recess.
22. In a machine for attaching cleats to shoes, a die-block, a holder movable upon the die-block and provided with a cleat-receiving recess, and spring-fingers secured to the holder for engagement with a cleat in the recess.
23. In a nailing machine, a work-support, a member having nail-holding openings and movable to present nails in different relations to work upon the support, nail-drivers operating in the openings, and transferring means movable to deliver nails to the holding member and having a member provided with nail-receiving openings and movable to arrange such openings in positions corresponding to those of the nail-holding openings.
24. In a nailing machine, a work-support, a member having nail-holding openings and movable to present nails in different relations to work upon the support, transferring means movable to deliver nails to the holding member and having a member provided with nail-receiving openings and movable to arrange such openings in positions corresponding to those of the nail-holding openings, and means dependent upon the positions of the holding and receiving members for controlling the delivery of nails.
25. In a nailing machine, a work-support, a member having nail-holding openings and movable to present nails in different relations to work upon the support, and transferring

means movable to deliver nails to the holding member and having a member provided with nail-receiving openings and movable to arrange such openings in positions corresponding to those of the nail-holding openings, the holding member and receiving member being provided with means arranged to control the delivery of nails.

26. In a nailing machine, a work-support, a member having nail-holding openings and movable to present nails in different relations to work upon the support, and transferring means movable to deliver nails to the holding member and having a member provided with nail-receiving openings and movable to arrange such openings to register with the nail-holding openings, there being means arranged to permit completion of movement of the transferring means only when the holding member and receiving member are positioned for registration.

27. In a nailing machine, a work-support, a member having nail-holding openings and movable to present nails in different relations to work upon the support, transferring means movable to deliver nails to the holding member and having a member provided with nail-receiving openings and movable to arrange such openings in positions corresponding to those of the nail-holding openings, and a retaining member for nails in the receiving openings, said retaining member being arranged to contact with the holding member to release the nails when the openings of the holding and receiving members correspond in position.

28. In a cleat-attaching machine, a shoe-support, a cleat-holding and nail-holding member arranged to present in different relations to a supported shoe the cleats and nails held, and means adjustable to deliver nails to the holding member in its different relations.

29. In a cleat-attaching machine, a shoe-support, nail-driving mechanism including a die-block, a cleat-holder and nail-holder movably mounted upon the die-block, a nail-loader, a nail-receiving member movable upon the loader and arranged for co-operation with the cleat and nail-holder in the movement of the loader, and means for fixing the

holding and receiving members in corresponding positions.

30. In a cleat-attaching machine, a shoe-support, nail-driving mechanism including a die-block, a cleat-holder and nail-holder movably mounted upon the die-block, a nail-loader, a nail-receiving member movable upon the loader and arranged for co-operation with the cleat and nail-holder in the movement of the loader, a nail-retaining shutter for the receiving member arranged to contact with the holding member, and means for fixing the holding and receiving members in corresponding positions.

31. In a cleat-attaching machine, a shoe-support, nail-driving mechanism including a die-block, a cleat-holder and nail-holder movably mounted upon the die-block, a nail-loader, a nail-receiving member movable upon the loader and arranged for co-operation with the cleat and nail-holder in the movement of the loader, means for fixing the holding and receiving members in corresponding positions, and means arranged to permit effective co-operation of the holding and receiving members only when their positions correspond.

32. In a cleat-attaching machine, a shoe-support, nail-driving mechanism including a die-block, a plug rotatable in the die-block and having a cleat-holding recess and a series of nail-holding openings, an oscillatory loader-arm, and a plug rotatable upon the arm and provided with a series of openings arranged for registration with the nail-openings in the holding plug.

33. In a cleat-attaching machine, a shoe-support, nail-driving mechanism including a die-block, a plug rotatable in the die-block and having a cleat-holding recess and a series of nail-holding openings, an oscillatory loader-arm, a plug rotatable upon the arm and provided with a series of openings arranged for registration with the nail-openings in the holding plug, and a nail-retaining shutter upon the loader-plug arranged for movement by contact with the die-block plug.

In testimony whereof I have signed my name to this specification.

ELMER R. POPE.
